UNITED STATES PATENT OFFICE.

JOSEPH C. CLUTTS, OF FORT THOMAS, KENTUCKY.

ELECTRIC FAN HEATER.

1,399,931.

Specification of Letters Patent. Patented Dec. 13, 1921.

Application filed November 23, 1920. Serial No. 426,065.

To all whom it may concern:

Be it known that I, JOSEPH C. CLUTTS, a citizen of the United States, and residing at Fort Thomas, in the county of Campbell 5 and State of Kentucky, have invented a new and useful Improvement in Electric Fan Heaters, of which the following specification is a full disclosure.

My invention relates to a portable motor 10 driven fan electric heater and particularly to the method of constructing and mounting the electric heater elements in front of the fan blades.

An object of the invention is to provide 15 a fan electric heater of a plurality of heater elements of blade form, disposed edgewise or at an angle to the fan blades, whereby the air circulated at a high velocity by the revolving fan is passed between the heater 20 blades and heated to an efficient degree.

Another object of the invention is to provide 25 a fan electric heater with blade heater elements, removably inserted upon a frame or holder for convenient insertion or removal for making renewals or increasing or decreasing the heating capacity by the number of blades employed.

Another object of the invention is to provide 30 a composite electric heater element in blade form, consisting of an electric current resistance member, disposed between sheets or laminations of insulating and heat radiating material, protecting the resistance material from the atmosphere, reducing oxidation and deterioration, and thereby increasing 35 the life and utility of the heater elements, also, to protect against contact for safety measures, adding stability to the product and advantages for production and 40 handling in commerce.

With these and other objects and features hereinafter appearing, the invention consists in certain novel combinations, construction and arrangement of parts herein- 45 after fully described with reference to the accompanying drawings, illustrating the preferred embodiment of the invention, and forming a part of the specification, and in the drawings like characters of reference 50 denote corresponding parts throughout the several views of which:

Figure 1 is a rear elevation of my heating apparatus attached to a commercial type of fan. 55 Fig. 2 is a horizontal section on line 2—2 of Fig. 1.

Fig. 3 is a detail plan view of the middle portion of one of the heating elements.

Fig. 4 is a combined section and edge view of the structure shown in Fig. 3. 60

Fig. 5 is a detail plan view showing the structure at the end of one of the heating elements.

Fig. 6 is an edge view of Fig. 5.

Fig. 7 is a horizontal section on line 7—7 of Fig. 5, a portion of the heating element supporting ring being shown.

The numeral 1 generally designates a commercial type of electric motor fan; 2, the base pedestal of the same; 3, the motor casing; 70 and 4, the fan.

Attached to the front face of the motor casing 3, by screws 4^a, are diametrical spider arms 5, extending forwardly of the fan 4, and fastened at 6 to a sheet metal heating 75

element supporting ring or frame 7, concentric with the fan shaft, and placed at a short distance in front of the fan. The frame 7 is of L-shaped or angle form in cross section, provides a front inturned 80

flange 8, forming a seat for an insulating annulus 9, of rectangular cross section and the inner circumferential face of the frame 7 is lined with heat insulating material 10.

Semi-circular electric current conductor 85 strips 11—11, each provided with a terminal 11^a, for making the circuit or wiring connections, are secured against the inner face of the annulus 9. Upon these conducting

strips are mounted and attached as at 12 in 90. vertically spaced and horizontally oppositely aligned pairs, spring switch clips 13 of conducting material. These switch clips 13 represent the commercial clips for knife electric

switches, having extending opposing spring 95 arms 14, slightly spaced apart for yieldingly clamping the terminals of the heating elements generally indicated at 20. These heating

elements are all of duplicate construction, only, varying in length, on account 100 of the employment of a circular frame. The heating coils 21 are formed by wrapping the wire around flat, laminated strips of mica

22, or about any suitable electric insulating and heat conducting and radiating material, 105 and are formed of two sections 23, each comprising a relatively long narrow portion 24,

and a relatively broad head portion 25, the head portions of the sections being interlapped centrally as at 26 (see Figs. 2, 3 and 110

4). Sectional laminated cover strips 30 of mica are placed above, below and against the

coils 21, are overlapped centrally as at 31, and their outer opposed edges fastened at intervals by clips 32, as shown, (see Fig. 7,) to hold the coils positioned between the cover strips. The cover strips are of equal width with the head portions 25, except at their ends 33, which are of equal width with the portions 24. This reduced formation of the ends of the cover strips is for a particular purpose, of which a description follows.

Since the cover strips are of equal length with the coil strips, and since the coil wire must be electrically connected with the spring clips and through them to the conducting strips 11, the coil wire passes from the strip 24 upwardly and is terminally coiled around the reduced ends 33 of the cover strips as shown at 35; and conducting clip-rings 35^a are then fastened as shown in contact with the terminal coils 35, and these rings are slipped between the arms 14 of the spring clips 13, to make the necessary electrical contact and to support said heating elements. The interlapping heads 25 of the coil strips and the overlapping ends 31 of the cover strips are fastened together as shown by a band 36.

One or more of the heating elements 20 may be easily and quickly removed or replaced. The motor current supply wires are shown at 40, and the heater current supply wires are indicated at 41. A switch 42 is interposed between the wire terminals 41^a and the terminals 11^a of the strips 11, by means of which the circuit for the heater can be controlled.

The electric heater unit can be attached to any type of electric fan, for heating the air forced outwardly by the fan.

40 The heating elements are removable, and any one of the same may be removed or dispensed with without destroying the efficiency of those remaining. The elements, being connected in parallel circuit connections with the opposite conductors, secured to the frame, provide for inserting or removing any number, for changing the capacity of the heater, and the utility of the unit is not impaired in the event of an element becoming destroyed or burned out.

45 The heater element carrying frame is shown of circular form merely to give symmetry to the structure as a whole, it being obvious that the outline of the frame may be variously modified.

50 The heater elements, as thin blade-like structures, are preferably mounted edge-wise to the fan, so that the air circulated by the revolving fan is passed over and between the blades of the unit, taking up the radiated heat without deflecting the air currents. Passing the air between the blades compels all of the air to pass through a heating zone created by the heater elements, thereby heating under the highest velocity

delivered by fan to an efficient degree, so that no special slow revolution fan need be employed nor the speed of the fan adjusted for heating. The construction admits of the fan to be utilized for either heating or 70 cooling purposes without removing the electric heater elements from the holder. The air direction of circulation is regulated by adjusting the angle of the motor or according to the provisions therefor employed in 75 the type of commercial electric motor driven fan employed.

Incasing the resistance material between laminations of mica protects the resistance material from the atmosphere, thereby reduces oxidation and thereby prolongs the life of the heater element and mica, being an adaptable transparent heat radiating material as well as insulator, provides a very efficient and durable covering, protecting 80 against any accidental contact with the electric current. The elements in a unit may be of the same or relatively varying capacity, depending upon the service requirements.

Having described my invention, I claim: 90

1. In a heat circulating apparatus, removable heating elements electrically connected in parallel and disposed in the air current path of an electric fan, electrical connections for said heating elements in circuit with the 95 fan power current, and means for making and breaking the said heating circuit independently of the fan circuit.

2. In a heat circulating apparatus, removable heating elements electrically connected in parallel and disposed in the air current path of an electric fan, means for supporting said heating elements, attached to the fan casing, electrical connections to said heating elements in circuit with the fan 100 power current, and means for controlling the heating circuit independently of the fan power circuit.

3. In a heat circulating apparatus, sectional heating elements covered by refractory material electrically connected in parallel and disposed to intercept the air current of an electric fan, means for removably attaching said heating elements to a supporting annulus, means for attaching said 110 annulus to a fan casing, electrical circuit connections between said heating elements and the fan circuit, and means for controlling said heating circuit independently of said fan circuit.

4. In a heat circulating apparatus, metallic resistance coils formed around the refractory heat conducting material, the said cores being disposed to intercept the air current of an electric fan, electric connections 115 from said coils to the fan power circuit, and means for the independent control of the heating coil circuit.

5. In a heat circulating apparatus, metallic resistance coils formed around the re- 120

- fractory heat conducting and the heat radiating material, the refractory heat conducting and radiating housings about said resistance coils, means for supporting said resistance coils in the path of an electric fan air current, electric circuit connections between said resistance coils and the said electric fan circuit, and switch means for the control of the resistance coil circuit independently of the fan power circuit.
6. In a heat circulating apparatus, metallic resistance coils, formed around refractory heat conducting and heat radiating material, refractory heat conducting and radiating housings about said resistance coils, and means for supporting said resistance coils in the path of an electric fan air current.
7. A device of the character described, an electric motor fan, a frame mounted adjacent the fan, having oppositely disposed electric current conductors mounted upon said frame and insulated therefrom, switch slips mounted upon said conductors and arranged in oppositely alined pairs, and an electric heater element for each pair of clips having its ends respectively insertibly engaged therewith.
8. A device of the character described, a revolving fan, an electric heater frame 30 mounted adjacent the fan, having a plurality of oppositely disposed heater element supporting and electric current conducting terminals, and a plurality of electric heater elements, each having its opposite ends respectively insertibly engaged with a pair of opposite companion terminals of said frame.
9. A device of the character described, a revolving fan, means for supporting an 40 electric heater element in front of said fan, and an electric heater element of blade form disposed edgewise of said fan.
10. A device of the character described, a revolving fan, a plurality of electric 45 heater elements, each of blade form, disposed parallel to each other and edgewise of said fan, whereby the revolving fan circulates the air over and between the heater elements.

In witness whereof, I hereunto subscribe my name, as attested by the two subscribing witnesses.

JOSEPH C. CLUTTS.
